ELECTRICAL MUSICAL INSTRUMENT

Leslie Edwin Alexander Bourn, Ashford, England

Application August 7, 1947, Serial No. 767,203
In Great Britain November 22, 1944Section 1, Public Law 690, August 8, 1946
Patent expires November 22, 1964

9 Claims. (Cl. 84—1.19)

1

This invention relates to electrical musical instruments of the kind comprising a multiplicity of individual frequency generators which are brought into operation selectively say by the actuation of stops and keys. The invention is especially but not exclusively applicable to electrical musical instruments of the electrostatic type, an example of which is described in U. S. Patents, Reissue #19,702 and #2,032,044.

In all the previous examples of musical instruments of the electrostatic type, the outputs from all the frequency generators have been paralleled together and connected to a common output amplifier. Thus the output voltages from any one or more of the total number of generators is considerably reduced by virtue of the shunting effect of the total capacity of all the remaining generators not in use. In certain cases, in which resistances are used to feed the polarising potentials to the respective generators, this deleterious shunting effect is still greater owing to the total number of resistances also shunting the output. Consequently, in previous musical instruments of the electrostatic type, the electrical response is small and high voltage polarizing is necessary. Also the signal/noise ratio is low.

of will now be described, reference being made to the accompanying drawings, wherein:

Figure 1 is a circuit diagram illustrating the essential circuits of a small organ in accordance with the invention;

Figure 2 is a circuit diagram illustrating an addition which may be incorporated in the arrangement of Figure 1;

Figure 3 is a circuit diagram illustrating the essential circuits of another small organ in accordance with the invention.

Referring first to Figure 1, the organ to which this figure relates comprises two manuals and pedals with thirty-six speaking stops derived from four ranks of tone families and two expression or swell pedals.

The tonal scheme of this organ is set out in the following Table I which gives the ranks and the manner in which they are distributed on 20 the manual and pedal departments. It will be seen for example that Table I indicates that a rank, or set, of ninety-six generator elements, all of flute tone, are playable in three different pitches on the Swell, six on the Great and five on the Pedal. The pitches are given in foot lengths in order to comply with standard nomenclature:

Table I

Rank	No. of Notes	Lowest Note	Swell (ft.)	Great (ft.)	Pedal (ft.)
Flute.....	96	CCC.....	16, 8, 4.....	16, 8, 4, 2½, 2, 1½.....	16, 10½, 8, 5½, 4.
Diapason.....	84	CC.....	8.....	8, 4, 2½, 2, 1½, 1.....	8.
String.....	84	CC.....	8, 4, 2½, 2, 1½, 1.....	8.....	
Reed.....	84	CCC.....	16, 8, 4.....	8.....	16, 8.

The present invention has for its object the provision of an improved electrical musical instrument in which, inter alia, this deleterious shunting effect in the case of instruments of the electrostatic type will be very much reduced.

A further object of this invention is the provision of an improved electrical musical instrument having a new and simplified system of connections.

The invention consists broadly in the arrangement that the generators feed the output through the medium of electronic valves. The valves may be arranged so that each one amplifies the output of a single individual generator, or several of the individual generators may be paralleled through a single valve. The outputs from the valves may be applied to an output amplifier and this supplies a loud speaker or loud speakers.

In order that the invention may be the more clearly understood, certain embodiments there-

40 The following Table II gives the stop names allocated to the various pitches in the order in which they appear in Table I:

Do	Trumpet	8 ft.	

To carry the above requirements into effect, a set of twelve generator structures 1 is required, only three of which are shown in the drawing. Each of these structures comprises a stationary disc 2 and a coaxial adjacent rotating disc 3. Much in the manner described in my prior Patent #2,032,044, each stationary disc 2 is engraved with coaxial rings 4 which are given wave forms and each rotating disc 3 is engraved with a grid which is adapted to scan the wave formed rings of the adjacent stationary disc. Unlike the arrangement described in patent #2,032,044, however, the wave forms of the rings 4 instead of being sinusoidal, correspond to the wave forms of the complete flute, diapason, string and reed tones. Thus, the twelve discs being engraved with wave forms for all the notes of the said four ranks, a total number of 348 rings 4, i. e. 29 per disc will be required. The scanning grids on the rotating discs 3 are connected to a source of polarization supply 5 of any suitable voltage. Owing to the increased efficiency which the present circuit provides, this voltage need only be of the order of, say, twenty volts.

The wave-forms engraved upon the discs and which form the generator elements may be derived by photographic methods directly from an oscilloscope trace of the actual tone required.

All the twelve structures 1 are identical both electrically and mechanically, but their discs 3 are driven at different speeds such that the twelve semi tones of the octave are produced. The lowest speed is 978.75 revs. per minute and, at this speed, a ring 4 having two complete waves per circle will produce 16 ft. C (ccc) at 32,625 c/c. Thus, according to Table I each disc 2 will be engraved with two rings each having two complete waves per circle, one of flute tone and the other of reed tone, and these rings in all will produce the bottom octave of those two ranks. For the next octave, rings with four waves per circle will be required, and each disc 2 will be engraved with four of such rings, two to continue the ranks already started and two to commence the diapason and string tone ranks. These are followed by four rings each of eight waves

per circle and so on until all the ranks are complete. Although not in accordance with Table I it may be desirable to represent the mutation pitches such as 2 $\frac{2}{3}$ feet, 1 $\frac{1}{3}$ feet etc., at the true harmonic frequencies, and not to borrow them from the musical scale.

Each individual ring 4 is connected, through a variable condenser 6, to the control grid of an electronic valve 7. By variation of the condenser 10, the strength of the input signal to the grid of the valve 7 may be varied. Each valve 7 has a resistance 8 in its cathode circuit for the purpose of producing negative current feed back, which stabilizes the performance of the valve and 15 also modifies the grid bias/gain characteristic. The value of these resistances is adjusted in order to make this characteristic uniform for all the valves.

The anodes of the valves are connected together in groups and those of each group are connected, through an anode resistance 9, which is common to that group, to a suitable plate current source. It is convenient to form two of such groups, one including all frequencies up to 20 about 200 c./s. and the other all frequencies above 25 200 c./s. The value of each resistance 9 must be low compared with the slope resistance of the valves in order to minimize intermodulation when a number of notes are sounding together. Each 30 group is connected through a condenser 10 to an output amplifier 11 and thence to the loud speakers 12.

The control grids of the valves 7 are normally kept at a negative potential equal to, or just in 35 excess of, the cut-off value, by means of a source of potential 13. This source communicates with each grid by way of resistances 14, 15 and 16 which are proper to that grid. Resistance 16 is a normal grid resistance and may be of the order 40 of two megohms. A condenser 17 is connected across resistances 14 and 15, and resistance 15, in conjunction with said condenser 17, acts as a low pass filter. Further mention of this network will be made hereinafter. Resistance 14 is normally 45 of the order of 1000 ohms, and its junction point 18 with resistance 15 is connected to all points in the keying system which require that particular tone, as will appear hereinafter. Thus, normally, although signals are being continuously 50 applied to the control grid of the valve 7 from the appropriate element 4, no signal is relayed through the valve.

Describing now the key and stop circuits, each key-board has associated therewith a number of 55 horizontal bus bars 19, corresponding to the pitches shown in Table I, and each key of that key-board has associated therewith a vertical trace 20 bearing a number of contacts 21, the arrangement being such that, upon the actuation 60 of any key, the corresponding trace 20 is moved vertically so that all the contacts 21 appertaining to that key are connected respectively to the bus bars 19. The key contacts 21 are connected to the appropriate points 18, and the bus bars 19 are energized according to the actuation 65 of the stops as will hereinafter appear.

It will be seen that there are, in the instrument being described, three distinct sets of bus bars 19, corresponding to the three keyboards. 70 In Figure 1 only the first three bus bars of the swell manual are shown, which, it will be seen from Table I, correspond to the 16, 8 and 4 foot pitches of the flute rank. The valve 7, which is illustrated, is shown cross-connected from its 75 junction point 18 to the second C on the 16 foot

bus bar 19 and to the first C on the 8 foot bus bar 19. Consequently, the tone to which this particular valve corresponds is the 13th note of the flute rank corresponding in pitch to 8 foot C (cc). The method of cross connecting the mutation pitches such as 2½ ft., 1¾ ft., etc., will be obvious to those skilled in the art. The traces 20 are normally operated by means of respective electromagnets, a single contact appertaining to each key closing when said key is actuated and energising the respective magnet which thereupon lifts the trace 20 and engages all the key contacts 21 for that key with the respective bus bars 19. The various intermanual couplers form part of these action circuits and require no description.

The references 22 and 23 designate conductors leading from the same point 18 to the other two keyboards.

The connection from each key contact 21 to its point 16 is by way of a resistance 24 and rectifier 25 in series as shown. The value of the resistance 24 is normally of the same order as that of the resistance 14, viz. 1000 ohms, and, owing to the low order of voltage necessary for the operation of these circuits, a single disc rectifier will suffice for each rectifier 25.

The bus bars 19 are supplied from a source of potential 27. Each bus bar is connected through a resistance 28, of value low compared to that of the key resistances 24, to the negative side of said source 27, and the energisation of said bus bars is effected from a common slider 29 which slides on a potentiometer resistance 30 connected across said source 27, said slider being adapted to be connected through respective resistances 31 and stop operated contacts 32 to the respective bus bars. The contacts 32 are brought into engagement with their bus bars according to the operation of the stops, and it will be seen that, whereas normally the bus bars are maintained at zero potential by means of the resistances 28, each time a contact 32 engages a bus bar is raised to a given potential depending on the resistance values. The position of the slider 29 and therefore the potential to which the bus bars 19 are raised, is controlled by means of a swell pedal 33.

The reference 34 denotes a second and similar potentiometer resistance, connected across the source 27, whose slider 35 is controlled by means of a similar swell pedal. This slider 35 feeds the bus bars of both the Great and the Pedal departments so that volume expression of both of these departments is under control by the same pedal. Alternatively, of course, each of these departments could have a potentiometer, slider and swell pedal to itself.

It will be understood that if, by way of example, the Lieblich Bourdon stop be "drawn," the appropriate contact 32 will close on the upper bus bar illustrated, and current will flow to said bus bar which will accordingly be raised to a potential value as determined by the setting of the swell pedal slider 29 and also by the value of the stop feed resistance 31. These resistances 31 are incorporated in order that the potential values and hence the loudness at which the stops will sound may be preset. They may, however, be omitted altogether if the maximum loudness is required for any particular stop. It is, however, generally desirable carefully to set the levels of the different stops in order to obtain a satisfactory tonal "tout ensemble" and balance.

If now the key C2 is operated, all the key contacts 21 appertaining thereto will close on all the

bus bars 19, but as, at the moment, only the upper bus bar is energised, only the single corresponding note will sound, as current will flow from only the energised bus bar through key contact 21, resistance 24 and rectifier 25, and through resistance 14 across which will appear a potential which is communicated to the control grid of the valve 7. Thus the bias on the said control grid, which normally prevents any signal from being passed on to the loud speakers, is reduced so that the vibrations generated by the corresponding ring 4 are relayed through the valve and transmitted to the loud speakers. It will be seen that the intensity or volume of the sound produced will be a function of the amount to which the bias has been reduced. It will also be appreciated that, whereas, in previous electrostatic instruments, control voltages of the order of hundreds were necessary, voltages of the order of about six volts are sufficient for controlling the grids in the present arrangement.

If now key C1 be operated as well as key C2, the bottom C of the rank will also sound through the appropriate contact, resistance, rectifier and valve. It will be noted that as all contacts on both keys C1 and C2 are now closed, the potential existing on the illustrated junction point 18 resulting from the operation of the key C2 will tend to flow to the second bus bar 19 (Gedackt) which is at zero potential, as its stop has not been "drawn." The presence of the rectifier 20, however, effectively prevents this and the defect of "robbing" accordingly does not take place.

If now, whilst the two keys C1 and C2 are in operation, the Gedackt stop is "drawn," thus energising the second bus bar 19, provided that the potential to which it is raised is greater than ½ that of the upper bus bar, additional current will flow through the resistance 14 and the particular note will sound at a louder level which, owing to the grid bias/gain characteristic of the valve, will be substantially in accordance with the expected increment caused by the two notes of two stops of equal pitch being sounded together.

It will be noticed from Table II that on the Swell, the String Rank draws twice at 8 ft. pitch under the names of Gamba and Salicional, similarly also on the Great the Diapason draws under the names of Open Diapason and Dulciana. In these cases, the Salicional and Dulciana is a softer rendering of the Gamba and Open Diapason, hence it is possible to use the same bus bar for both in each case, the only difference being that a greater value of stop feed resistance is used for the softer stops. The employment of the same stop sounding at different strengths is known as "double-winding" the name being taken from the practice of sounding organ pipes on lower wind pressures.

It will be further noticed that on both manuals, stops appear under the name of "Mixture IV Ranks." Such stops are well known to organ builders and are used to enhance the tonal blend of the instrument. This is a case of double-winding where bus bars of the requisite pitches already exist, but if not additional bus bars must be added where necessary. Each stop in these cases cited operates four separate contacts 32 each associated with the appropriate bus bars.

On the Great, it will be seen that a synthetic Clarinet stop has been included. This is yet another instance of double winding and in which a new known tone may be produced from a combination of existing tones. It is obvious that any such combinations may be employed for the pro-

duction of a very large variety of new and novel effects.

As was mentioned earlier, a low-pass filter in each grid bias feed is incorporated consisting of resistance 15 and condenser 17. The function of these circuits is to assimilate as nearly as possible the tonal build-up or attack of an organ pipe. It will be seen that as the potential is suddenly applied at the point 18, the potential rise is gradual across the condenser 17, as is also the potential applied to the valve. Such a circuit is essential for the avoidance of "key clicks." The component values are graded throughout the musical compass so that the trebles are prompter in speech than the basses; the reed is made prompter than, say, the string.

The tones may be made to die away more gradually by the incorporation of an additional condenser 36 and a rectifier 37 shunted by a resistance 38 as shown in Figure 2. Thus the rectifier 37 is connected between the point 18 and the resistance 15, and the condenser 36 is connected between the junction point of the rectifier 37 and the resistance 15 and the positive terminal of the source 13. It will be seen that the rectifier 37 will allow the condenser 36 to charge rapidly and to slowly leak away through the resistance 38.

In the instrument described, all tone ranks are represented by elements 4 mounted upon the same set of generator discs. In more advanced instruments, it may be beneficial to provide a separate set of discs for each rank, the associated valves 7 being connected so that their outputs feed into amplifiers and loudspeakers individual to each set of discs. Each rank will then have an entirely independent output and also an independent origin. As the discs are usually belt driven, there will exist slight differences of pitch and steadiness. Such differences, if not too great, are of considerable importance to the overall effect, as each separate tone then sounds as an independent instrument and stands apart from the other tones. This is not the case when all frequencies are locked together with mechanical precision as is the case when all tones are derived from the one set of discs.

In the embodiment just described with reference to Figures 1 and 2 each individual element 4 has its own proper associated valve 7, and thus any shunting load due to the inoperative generator elements is prevented. As even the smallest instrument entails the use of approximately one hundred generator elements, it may be stated approximately that the output of a single generator element would be reduced to $1/100$ by the shunting effect of the remaining elements. Obviously the shunting effect can be in a considerable measure reduced, although not so fully as in the embodiment above described, if each valve is associated with a group of generator elements instead of with one individual generator element. Such an arrangement is illustrated in Figure 3, which has the additional advantage of a new and simplified system of connections.

This figure illustrates an instrument which may be of the same general type and tonal scheme as that of Figure 1. Its principal difference from the instrument of Figure 1 is, firstly, that, instead of having twelve generator structures 1 corresponding to the twelve semi tones of the octave, it has a generator structure 1 for each key of the instrument and a valve 7 for each generator structure. The wave forms of the rings 4 on each stationary disc 2, and the speed of rota-

tion of the corresponding rotating disc 3 are such that said rings 4 are adapted to produce all the frequencies, whether they are pure or complex, which are required by that particular key.

Although, by such an arrangement, the maximum efficiency is not attained, certain other advantages are gained, for example, for a two manual instrument with pedals, a total of 154 valves are required, compared with the 348 required by the arrangement of Figure 1. Also the number of contacts operated by a single key is reduced to a single contact, other contacts only being necessary for couplers. It will be appreciated that the number of generator structures could, if desired, be reduced to one half by employing two stationary discs 2 in each structure, one each side of a single rotating disc 3, which would bear a scanning electrode on each face.

Although the principle embodied in Figure 3 lends itself perfectly to the use of rings 4 adapted to generate complex tones as in the case of Figure 1, the rings 4 in the actual arrangement to be described generate pure tones and the tones are mixed by circuit control. It is assumed that there are ten harmonic frequencies per key, or, in other words, that each stationary disc 2 bears ten rings 4, adapted to generate the said ten harmonic frequencies. It may be noted in passing that, with this arrangement, the voltage generated by a single element 4 will be reduced to approximately one tenth owing to the shunting effect of the remaining 9 elements 4 on the same disc 2 and associated with the same valve 7. This, however, represents a considerably higher efficiency than has been obtained by previous systems.

The precise number of stops or tonal varieties which could be obtained with the above number of harmonics is theoretically large, but, with so small a complement of harmonics, the practicable number would probably be about twelve. The frequencies per note in the example being described are as follows: In foot pitches they are 16, 8, $5\frac{1}{2}$, 4, $2\frac{2}{3}$, 2, $1\frac{1}{3}$, $1\frac{1}{2}$, $1\frac{1}{4}$ and 1. These correspond to harmonics 1, 2, 3, 4 at 16 ft pitch, 1 to 8 at 8 ft. pitch, 1 to 4 at 4 ft. pitch and 1 and 2 at 2 ft. pitch. Table III gives the number of waves per circle of the elements 4 on the different discs 2, and the speeds at which they are run for the manuals. For the pedals, the same discs are used as for the first 32 notes of the manuals.

Table III

Notes	Elements—Waves per circle	Speeds, R. P. M.
1-12.....	2, 4, 6, 8, 12, 16, 20, 24, 28, 32.	978.75—1,846
13-24.....	4, 8, 12, 16, 24, 32, 40, 48, 56, 64.	978.75—1,846
25-36.....	8, 16, 24, 32, 48, 64, 80, 96, 112, 128.	978.75—1,846
37-48.....	8, 16, 24, 32, 48, 64, 80, 96, 112, 128.	1,957.5—3,692
49-61.....	8, 16, 24, 32, 48, 64, 80, 96, 112, 128.	1,957.5—3,915

In the circuit of Figure 3 only three generator structures 1 are shown. The scanning grids which are engraved on the rotating discs 3 are each connected, through a variable condenser 6, to the control grid of a valve 7. The anodes of the valves 7 are paralleled as in Figure 1 and the manner in which they are fed and in which the outputs are supplied to the loud speakers is the same as in Figure 1 as will be seen from the same references which are applied to like parts in the two figures. Also, the network by which the control grids of the valves 7 are normally kept at a potential equal to, or just in excess of, the cut-off value, by means of a source of potential

13, is the same as in Figure 1 as will be seen by the references. In the present case, the resistance 14 may be of any convenient value as it serves only to hold the grid at the cut-off value from the source 13.

Also as in Figure 1, a source of potential 27 is provided, having potentiometer resistances 30 and 34 connected thereacross, said potentiometers being provided with sliders 28 and 35, actuated by swell pedals, for feeding the different departments. In the present case, however, said sliders do not supply the bus bars 19, but each one supplies a bus bar 39, which is common to all the keys 40 of that department. As will be seen from the drawings, when any key 40 is depressed, the bus bar 39 is connected through a contact 41 with the point 18 appertaining to that particular key.

The elements 4 corresponding to 16 ft. pitch on all the discs 2 are connected together throughout the entire compass of the manual (or other department) by a common lead 42, and likewise the 8 ft., 5 1/3 ft. elements and so on. These leads 42 are respectively connected to the bus bars 19. The bus bars 19 in the present case are adapted to be polarised by a source of potential 43 and are normally maintained at zero potential by being connected through resistances 28 to the negative side of said source. In the present case, these resistances 28 may be of the order of 0.1 megohm.

Each stop has an associated trace 44 and said trace carries contacts 45 which are connected through respective stop-feed resistances 46 to the positive of the source 43, and when the stop is "drawn" the trace is moved so as to bring its contacts 45 into engagement with the appropriate bus bars 19. Each stop will, of course, close contacts 45 on to the bus bars corresponding to the harmonics in the required tone, and the resistances 46 are, of course, chosen so as to provide the required harmonic strengths.

It will now be seen that, if a key 40 is depressed, current will flow through the resistance 14 corresponding to said key, and the junction point 18 will be raised to a potential determined by the setting of the slider 29 operated by the swell pedal. The corresponding valve 7 will accordingly be restored to its amplifying condition, but, if no stop is "drawn," the elements 4 associated with said valve will be at zero potential and no sound will result.

If now a 16 ft. flute stop is drawn requiring only the single harmonic, a contact will close only on the 16 ft. bus bar 19 and this will cause all the 16 ft. elements 4 throughout the whole compass to become polarised, but as all the valves 7 except that corresponding to the depressed key are non-transmissive the 16 ft. harmonic will sound only in the case of the note represented by that stop. In like manner, if a stop is drawn requiring a number of harmonics, the corresponding bus bars 19 will be polarised, and, when a key is depressed, those harmonics will sound on the note corresponding to that key.

If two stops be drawn together, both of which involve the polarisation of the same bus bar, say the 16 ft. bus bar, this bus bar will be polarised to a higher potential owing to the two resistances 46 in parallel. Thus, the correct additive effect will be obtained.

A tremulant of the amplitude modulation type may be put into effect by modulating the potential applied to either the second or third grids of the valves 7 (which are shown as pentodes) by means of an electronic oscillator. A frequency

modulation tremulant may be provided by oscillating the normally stationary discs 2 in the manner described in British Patent No. 448,193.

An instrument with a separate disc structure per key as in Figure 3 may be used to form what is known as a Celeste. This is a second tone usually of a stringy nature which is nearly but not quite in tune with the remainder of the tones. Thus, when this is played in combination with other stops a slow beating takes place. In order that such an effect shall be artistic, the speeds must be carefully graded throughout the compass. This can only be accomplished where belt drive for the discs 3 is used, in which case, by means of adjustable pulleys, the beats may be graded throughout the compass. These additional discs for the Celeste are connected so that the rotors 3 are parallel to the appropriate grids of valves already in use. The elements are joined as before but to form a separate set of bus bars and stops. It is usually more economical to employ a single set of complex waves which are energized at will by a single stop.

In order to reduce substantially the number of discs in the arrangement of Figure 3, this may be modified in such a way that all the C's are arranged on a single disc and likewise all the C#'s, D's, etc. The number of valves will still be the same as the number of keys and there will thus be several keys and valves per disc.

This may be done by connecting the scanning grids so that they are maintained at zero potential with regard to the negative end of the source 13. The elements 4 pertaining to the same key would be each connected through a condenser to the grid of the pertaining valve 7. The junctions between the said element 4 and the said condensers would be each connected through a high value resistance to the appropriate leads 42 and thence to the bus bars 19.

This last named embodiment is, however, less efficient electrically than that of Figure 3 owing to the additional shunt resistive load imposed across the output due to the presence of the resistances.

We claim:

1. An electrical musical instrument comprising loud speaker means, a multiplicity of frequency generators, said generators including electrodes between which the frequencies are generated in the form of undulating potential differences induced electrostatically, electronic valves through which said frequencies are transmitted to said loud speaker means, said electronic valves each having a control electrode, means whereby the control electrodes of said valves are normally kept at a negative potential for rendering said valves non-transmissive, said last named means comprising a source of negative potential, three resistances in series between each control electrode and said source, and a condenser connected across two of said resistances, and control means for selectively raising the potentials of said control electrodes and thereby rendering said valves selectively transmissive, said control means comprising a source of positive potential and means for selectively connecting the points between those pairs of resistances across which the condensers are connected to said source of positive potential.

2. An electrical musical instrument comprising loud speaker means, a multiplicity of frequency generators, said generators including electrodes between which the frequencies are generated in the form of undulating potential differ-

ences induced electrostatically, electronic valves through which said frequencies are transmitted to said loud speaker means, a resistance in the cathode circuit of each valve for the purpose of producing negative current feed back, the values of all the cathode circuit resistances of all the valves being adjusted to make the grid bias gain characteristic substantially uniform for all the valves, and control means for rendering said electronic valves selectively transmissive.

3. An electrical musical instrument comprising loud speaker means, a multiplicity of frequency generators, said generators being arranged in groups, those of each group corresponding to the partials of one respective note only, a common output from the generators of each group to said loud speaker means, which output is individual to that group only, and means for controlling said common output.

4. An electrical musical instrument comprising loud speaker means, a multiplicity of frequency generators, said generators being arranged in groups, those of each group corresponding to the partials of one respective note only, a common output from the generators of each group to said loud speaker means, which output is individual to that group only, stops for controlling the energization of said generators, and keys for respectively controlling said common outputs, each key being individual to each common output.

5. An electrical musical instrument comprising loud speaker means, a multiplicity of frequency generators, said generators being arranged in groups, those of each group corresponding to the partials of one respective note only, a common output from the generators of each group to said loud speaker means, which output is individual to that group only, stops for controlling the energization of said generators, electronic valves connected in said common outputs, each electronic valve being individual to each common output, and keys for controlling said electronic valves and thereby respectively controlling said common outputs.

6. An electrical musical instrument comprising loud speaker means, a multiplicity of frequency generators, said generators including electrodes between which the frequencies are generated in the form of undulating potential differences induced electrostatically, said generators being arranged in groups, those of each group corresponding to the partials of one respective note only, each group comprising a plurality of individual electrodes and a common scanning electrode which is individual to that group only, a common output from the generators of each group to said loud speaker means which output is individual to that group only and is taken from said common scanning electrode, and means for controlling said common output.

7. An electrical musical instrument comprising loud speaker means, a multiplicity of frequency generators, said generators including electrodes between which the frequencies are

generated in the form of undulating potential differences induced electrostatically, said generators being arranged in groups, those of each group corresponding to the partials of one respective note only, each group comprising a plurality of individual electrodes and a common scanning electrode which is individual to that group only, a common output from the generators of each group to said loud speaker means which output is individual to that group only and is taken from said common scanning electrode, stops for controlling the energization of said individual electrodes, and keys for respectively controlling the common outputs.

8. An electrical musical instrument comprising loud speaker means, a multiplicity of frequency generators, said generators including electrodes between which the frequencies are generated in the form of undulating potential differences induced electrostatically, said generators being arranged in groups, those of each group corresponding to the partials of one respective note only, each group comprising a plurality of individual electrodes and a common scanning electrode which is individual to that group only, a common output from the generators of each group to said loud speaker means which output is individual to that group only and is taken from said common scanning electrode, stops for controlling the energization of said individual electrodes, electronic valves connected in said common outputs, and keys for controlling said electronic valves and thereby respectively controlling said common outputs.

9. An electrical musical instrument comprising loud speaker means, a multiplicity of frequency generators, said generators including electrodes between which the frequencies are generated in the form of undulating potentials induced electrostatically, electronic valves through which said frequencies are transmitted to said loud speaker means, said electronic valves being individual to said generators each to each, means for permanently energising said generators, bus bars, stops for selectively polarizing said bus bars, and keys for selectively connecting said valves to said bus bars for rendering said valves selectively transmissive.

LESLIE EDWIN ALEXANDER BOURN.
